Primary Examiner — Karen E Eldridge Powers*(74) Attorney, Agent, or Firm* — Christensen O'Connor Johnson Kindness PLLC(57) **CLAIM**

The ornamental design for a powered applicator brush for hair, as shown and described.

DESCRIPTION

FIG. 1 is a front, top, left perspective view of a powered applicator brush for hair in accordance with an embodiment of the design;

FIG. 2 is a rear, bottom, right perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left elevation view thereof; and,

FIG. 8 is a right elevation view thereof.

The broken lines shown in the drawings illustrate portions of the powered applicator brush for hair that form no part of the claimed design.

1 Claim, 5 Drawing Sheets(56)
